(No Model.)

A. R. PERKINS.

SHIRT.

No. 258,110.

Patented May 16, 1882.

UNITED STATES PATENT OFFICE.

ALBERT R. PERKINS, OF NEWTON, ASSIGNOR TO SIMONS, HATCH & WHITTEN,
OF BOSTON, MASSACHUSETTS.

SHIRT.

SPECIFICATION forming part of Letters Patent No. 258,110, dated May 16, 1882.

Application filed February 27, 1882. (No model.)

To all whom it may concern:

Be it known that I, ALBERT R. PERKINS, of Newton, of the county of Middlesex, of the State of Massachusetts, have invented a new and useful Improvement in Shirts; and I do hereby declare the same to be described in the following specification and represented in the accompanying drawings, of which—

Figure 1 is a front elevation, and Fig. 2 a horizontal section, of a shirt of my improved kind, the latter figure being represented on an enlarged scale. Figs. 3 and 4 are hereinafter described.

My invention has reference to double-breasted shirts; and it consists mainly in forming the front of the body with a slit or opening extending down its middle from the neck or collar to, or nearly to, the waist, and fastening to the body, at or near the edges of the slit, two flaps or semi-fronts, each of said semi-fronts being capable of being lapped underneath the upper part of the body, while the other semi-front is lapped over or on the outside the body. The cloth at each edge of the slit I usually narrowly fold, and stitch the lap down upon the cloth, and I generally likewise finish each edge of each of the semi-fronts and apply to the rear face of such semi-front a lining, and extend such lining underneath and stitch it to the next adjacent part of the body.

Fig. 3 represents the upper portion of the front of the body A as slit down its middle, from its upper edge to, or nearly to, the waist, the slit being shown at a. Fig. 4 is a representation of the form of each of the semi-fronts. Having thus slit the body, I usually narrowly plait it along the line b c d e f and stitch down the plait, and make in the cloth, at short distances from and parallel to the plait, one or more rows of stitching. Next I secure to the slit body-front A the two semi-fronts B B, one being fastened to it on one side of the slit, at or near one edge of it, and the other being fastened to it on the other side of the slit, or at or near the other edge thereof.

The shirt so made will be double-breasted and have the appearance of having two breast-fronts to its body, each of the semi-fronts be-

ing capable of being lapped on the shirt-body, while the other is lapped underneath it. Each 50 semi-front, near its free edge, is to be provided with button-holes to receive buttons fixed to the body of the shirt, all being to enable the semi-front, when lapped over the shirt-body, to be buttoned down thereto. Instead of buttons and button-holes, other proper separable fastenings may be used.

At the middle of each breast of the shirt there may be two rows of lacing-holes and a lacing run through such, and there may be in the collar or neckband holes and eyelets to receive the lacings.

My improvement is particularly adapted to the manufacturing of shirts of flannel, such as are usually termed "overshirts," as worn by 65 riders of bicycles.

I do not claim a shirt having its neckband attached to the body only at the back of the neck-opening and the bosom attached at its upper edge only to the front of the neckband 70 and shirt-body, as represented in the United States Patent No. 169,333, as my invention differs materially therefrom, inasmuch as it has two semi-fronts sewed to opposite edges of a slit made downward within the front of the 75 body, as hereinbefore represented, neither of such semi-fronts being otherwise sewed to the body.

I claim as my invention—

1. A shirt-body, A, slit down the middle of 80 its front from the neck to, or about to, the waist of such body, as described, in combination with two separate semi-fronts, B B, arranged with the slit a and sewed to the edges thereof, all being substantially as set forth. 85

2. A shirt-body slit down the middle of its front from the neck thereof and plaited, as described, in combination with two separate semi-fronts, arranged with the slit a and sewed to the edges thereof, all being substantially as set 90 forth.

ALBERT R. PERKINS.
